CLAIM

The ornamental design for a wireless speaker, as shown and described.

DESCRIPTION

FIG. 1 is a perspective view of a wireless speaker showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is an exploded view thereof.

FIG. 9 is a bottom view thereof, shown without the base for ease of illustration.

FIG. 10 is a top view thereof, shown without the speaker portion for ease of illustration; and,

FIG. 11 is a bottom perspective view thereof, shown without the base for ease of illustration.

The broken lines in the figures illustrate the portions of the design that form no part of the claimed design.
